UNITED STATES PATENT OFFICE.

EDWARD B. STEPHENSON, OF SCHENECTADY, NEW YORK.

ELECTROMECHANICAL RECORDING MECHANISM.

Application filed February 13, 1924. Serial No. 692,575.

(GRANTED UNDER THE PROVISIONS OF THE ACT OF MARCH 3, 1883, 22 STAT. L., 625.)

The invention described herein may be used by the Government, or any of its officers or employees in prosecution of work for the Government, or by any other person in the United States, without payment to me of any royalty thereon.

This invention from a generic aspect relates to mechanism for recording time intervals, more especially it is directed to an electro-mechanical recording apparatus particularly applicable to a subaqueous system of artillery fire adjustment, utilizing water as a transmitting medium, the impact of the projectile striking the water as a source of the pressure wave and hydrophones as detectors.

In pending application Serial No. 435,510, filed January 6, 1921, there is shown and described a subaqueous system of artillery fire adjustment based on the theory that— (1) a projectile striking the water produces a pressure pulse or wave having a circular wave front, (2) there is a time interval between the arrival of the pressure wave at two or more stations located at definitely known and equally distant points, (3) the differences in the time of arrival at the different stations, taken in connection with the constant known rate of propagation of the pressure wave in water, will enable determination of the source of the disturbance, (4) the sources of the pressure wave likewise the position of the target being known the correct artillery adjustment can readily be ascertained.

In the practical application of this invention, the record of the time interval between the arrival of the pressure pulse or wave at two or more detector stations was produced either mechanically, by means of a stylus operating on a smoked surface moving at a uniform rate of speed, or photographically through the instrumentality of a spot of light focused on a sensitized paper also travelling at uniform speed.

As time is an important factor in the problem of accurately ranging artillery fire, it is obviously imperative that the final result of the fire be obtained as quickly as possible and therefore the several steps contributory to this result must be made with

the least possible delay. For this reason neither the mechanical nor photographic recording devices heretofore employed have been entirely satisfactory.

55

When the mechanical recorder was utilized, owing to the impossibility of impressing timing lines transversely across the whole record, measurement of the time interval was extremely difficult, while with the use of the photographic recording mechanism, there was an objectionable time loss due to the necessity of developing the film before the record could be read.

Moreover, with both of these recording devices it was necessary to algebraically subtract each reading from the preceding one and this involved an additional loss of time and likewise introduced a further objectionable feature arising from the possibility of personal errors.

It is therefore the aim and purpose of this invention to overcome the defects mentioned and provide an electro-mechanical recording mechanism capable of automatically functioning to afford a direct reading of the time interval between the arrival of the pressure wave or pulse at two or more suitably spaced detector stations.

With the above and other objects in view this invention consists in certain novel details of construction, combination and arrangement of parts to be more specifically hereinafter set forth and claimed.

Briefly stated, this invention embodies a recorder circuit, pair of contact switches included in the circuit, one being normally open, the other closed, a pair of detector stations submerged off shore and arranged in suitably spaced relation, means to effect actuation of the normally open contact switch and completion of the recorder circuit, when a pressure pulse or wave, produced by a projectile striking the water, encounters one of the detector stations, additional means to open the remaining contact switch and disrupt the recorder circuit when the pressure pulse or wave contacts with the companion detector station, and recording means in the recorder circuit adapted to indicate the energized period of the circuit and consequently the time inter-

75

90

100

val required for the pressure pulse or wave to travel from one detector station to the other.

Referring more particularly to the accompanying drawings, in which corresponding parts are indicated by similar reference characters:

Fig. 1 is a diagrammatic view illustrating the detector stations, central station, reversing switch, relays, electro-magnets controlling the electro-mechanical recording apparatus, and the operating circuits for these components.

Fig. 2 is a diagrammatic view illustrating the listening stations, the direction finders, and the microphone circuits controlled thereby and disclosing the disposition of the direction finders with respect to the detector stations, the circuits of which are partially shown.

Fig. 3 is a front elevation of the electro-mechanical recording apparatus, and

Fig. 4 is a side elevation thereof.

In order to facilitate discussion of this invention it will be further considered under the following headings:—Detector installation, Central station, Direction finders, Operation and conclusion.

30 *Detector installation.*

To obtain the initial indication of the pressure wave resulting from a projectile striking the water, a series of hydrophone detector stations, three in number and indicated D₁, D₂, and D₃, are submerged in equi-spaced relation and at a sufficient distance off shore to avoid water noises on shore and afford an uninterrupted water path between the stations and the source of the pressure wave or pulse.

As it is essential to the successful operation of this invention that the hydrophone detector stations respond only to a characteristic pressure pulse or wave, a specially designed hydrophone is employed consisting of a rigid shell (1) within which is diametrically positioned a strip of thin spring steel (2) adjustably tensioned for tuning. Affixed to the central portion of the strip (2) is an inertia element in the nature of an iron disc, constituting a movable contact (3). A stationary contact (4) relatively adjustable with respect to the movable contact (3) is suitably mounted within the shell as shown in Figure 1 of the drawings.

The dimensions of the hydrophone shell, the length, width, thickness, tension of the steel strip, weight of the iron disc or inertia element and relative position of the movable and stationary contacts, are so adjusted and proportioned as to give maximum sensitivity to the characteristic pulse or pressure wave produced by the projectile striking the water, as will be apparent without further discussion.

As the preceding structure forms no part of the present invention, it is referred to merely for descriptive purposes, therefore shown, more or less diagrammatically in the drawings.

70

Central station.

The several detectors D₁, D₂, and D₃ are electrically connected with a central station wherein is located an electro-mechanical recording apparatus, functioning to indicate the differences in time of arrival of the pressure wave or pulse at two or more of the detector stations.

This recording apparatus in its present embodiment consists of a suitable frame comprising base (4'), parallel uprights (5) and a cross-head (6), suitably braced and connected at its inner end to the uprights (5). The forward edge of the cross-head (6) is provided with a brake-shoe (7) for a purpose hereinafter to be described.

Rotatably mounted on the base (4') below the brake-shoe (7) is a large heavy drum (8) driven by a direct current motor (9) through reduction gears (10). To enable rotation of the drum (9) at a constant peripheral speed of 20 cm. per second a governor (11) of conventional type is operatively connected with the motor shaft as clearly shown 95 in Figure 3 of the drawing.

The size of the drum (8) and rotation thereof at constant speed is highly important to the accuracy of this apparatus and must be such as to prevent change in speed 100 of the drum when the time indicating discs, hereinafter mentioned, are brought into contact therewith. As the load is constant and the rate of rotation low, no difficulty is experienced in governing the driven motor 105 either mechanically or electrically to .05 percent, which is the required degree of speed control.

Interposed between drum (8) and brake-shoe surface (7) are two light weight discs 110 (12) and (12') each of which is rotatably journaled in the forward extremity of an arm (13), the opposite end of which is pivotally mounted on rocker shaft (14). A spring (15) positioned between each of the 115 arms (13) and cross-head (6) normally maintain the discs (12) and (12') in engagement with brake-shoe (7).

The rotary movement of the drum, likewise the relative dimensions of discs and drum are such that the discs (12) and (12') will make one revolution in exactly two seconds. These discs are graduated around their periphery so that two mm. equals .01 seconds. In this connection it would be 125 practical to estimate to a tenth of a division thus affording readings to the thousandths of a second.

Assuming a base line of thirty-six yards or less and a pressure pulse velocity of six- 130

teen yards per second, the maximum time interval would not exceed two seconds. This scale would therefore require discs of 6.37 cm. radius or approximately five and a ⁵ quarter inches in diameter.

As the discs (12) and (12') are started by contact with drum (8) and stopped by engaging brake-shoe (7), it is evident, a very slight time loss occurs, which, however, may ¹⁰ be minimized to a large extent by constructing the brake-shoe (7) of the same material and with the same curvature as the drum (8) so that the starting and stopping processes will be almost identical. Moreover, ¹⁵ this slight time interval, may readily be compensated for by shifting the zero point as the error is constant within the required limits of accuracy.

Mounted immediately below and intermediate the extremities of arms (13) are electro-magnets (15') and (16) respectively, positioned to cooperate with the armature surfaces (17) carried by the arms, so that the electro-magnets when energized, will ²⁰ draw the arms downwardly and place the discs (12) and (12') in contact with the rotating drum (8), for a purpose to herein-after appear.

To energize the electro-magnet (15') and ³⁰ (16) they are included in circuits 1₁ and 2₁ respectively. Circuit 1₁ comprises battery (18) or other suitable source of electrical energy, conductor (20), electro-magnet (15'), conductor (21), contact (22), armature switch (23), conductors (24) and (25), armature switch (27), contact (28) and conductor (29).

Circuit 2₁ comprises battery (30), conductor (31), electro-magnet (16), conductor ⁴⁰ (32), contact (33), armature switch (34), conductors (35), (25) and (24) armature switch (23), contact (36) and conductor (37).

To retain the armature switches (27), ⁴⁵ (23) and (34) in a normal position with respect to circuits 1₁ and 2₁ each is provided with a retractile spring (38). After actuation of the switches to circuit closing or disrupting positions, they are automatically ⁵⁰ locked therein by spring latches (39), which may be manually or electrically released depending on the exigencies of the situation.

The armature switches in conjunction with their respective solenoids constitute relays R₁, R₂ and R₃, which are included in three relay circuits each including a hydrophone detector station D₁, D₂, or D₃, reversing switch S and one of the relays R₁, R₂ or R₃.

The relay circuit including relay R₁, comprises ground connection (40), movable and stationary contacts (3) and (4) of the hydrophone detector station D₁, conductor ⁶⁰ (41), blade (42) of reversing switch S, contact (43), conductor (44), relay R₁, con-

ductors (45) and (46), battery or other suitable source of electrical energy (47) and ground connection (48).

The relay circuit of detector station D₂ comprises ground connection (49), movable ⁷⁰ and stationary contacts (3) and (4) of hydrophone detector station D₂, conductor (50), blade (51) of reversing switch S, contact (52), conductor (53), relay R₂, conductors (45) and (46), battery (47) and ground connection (48).

The relay circuit for the conductor station D₃ embodies ground connection (54), ⁸⁰ movable and stationary contacts (3) and (4) of hydrophone detector station D₃, conductor (54), switch blade (55) of reversing switch S, contact (56), conductor (57), relay R₃, conductors (45) and (46), battery (47) and ground connection (48).

As the relays R₁, R₂ and R₃ are arranged ⁸⁵ to function in the order mentioned, while the pressure pulse or wave may approach the detector stations D₁, D₂ and D₃, from the right or left, it is necessary to provide for a reversal of the order in which the detector stations effect energization of the relays and for this purpose the switch S is formed with reversing contacts (58), (59), and (60) disposed opposite and in alinement with the contacts (43), (42) and (56). Contact (60) is connected with conductor (57) by conductor (61); contact (59) with conductor (53) by conductor (62) and contact (58) with conductor (44) by conductor (63).

With the contacts connected in this manner it is evident when switch blades (42), (51), and (55) are thrown into engagement with contacts (60), (59) and (58) respectively, detector station D₃ functions to complete the circuit of relay R₁; detector station D₂ of relay R₂ and D₁ of relay R₃.

Direction finders.

In order to select the disturbances to be located and also to determine the position ¹¹⁰ of reversing switch S, two direction finders, in the nature of hydrophones D₄ and D₅ are submerged off shore well in advance of the detector stations D₁, D₂ and D₃. The positions of the hydrophones with respect to ¹¹⁵ those of the detector stations are such that the disturbance from any splash in the normal field of fire must contact with either direction finders D₄ or D₅ at least a half a second before it encounters detector stations ¹²⁰ D₁, D₂ or D₃.

The direction finders are connected binaurically to enable the operator, not only to hear the disturbance and decide whether or not it should be located, but also to determine which of the detector stations D₁ or D₃ the pressure pulse or wave will strike first, (whether it will strike detector station D₁ or D₃) so that the switch S may be thrown to the proper position. Each direc- ¹²⁵ ¹³⁰

tion finding station controls a microphone circuit including ground connection (64), fixed and movable contacts (65) and (66) of the hydrophone direction finder, conductor (67), battery (68), conductor (69), microphone (70) and ground connection (71).

Operation and conclusion.

10 Let it be assumed that a projectile enters the water at a point, which the listening operator determines to be to the right of detector station D_1 , through the instrumentality of the binaurically connected stations 15 D_4 and D_5 . Accordingly reversing switch S is thrown to the position shown in Figure 1 and the detector stations D_1 , D_2 , and D_3 are thus placed in the proper order to indicate the difference in time of arrival of the 20 pressure wave at the respective stations.

When the pressure pulse or wave impinges the diaphragm of detector station D_1 , relay R_1 is energized, armature switch (27) brought into engagement with contact (28) 25 and circuit 1_1 closed. Completing this circuit energizes electro-magnet (15'), pulls down the arm (13) of the recording apparatus and sets the disc (12) in rotation by frictional contact with the drum (8) which 30 is rotating at a uniform peripheral speed of twenty cm. per second. The disc (12) continues to rotate until the pressure pulse or wave reaches detector station D_2 , whereupon R_2 is energized, armature switch (23) 35 and contact (22) disengaged and the circuit 1_1 disrupted. Opening circuit 1_1 , deenergizes electro-magnet (15') and permits spring (15) of arm (13) to restore the disc (12) to its original braking position with respect 40 to brake shoe (7), to immediately terminate its rotary movement. Simultaneous with disruption of circuit 1_1 , the armature switch (23) having been placed in engagement with contact (36), completes circuit 2_1 , energizes 45 electro-magnet (16), pulls down arm (13) of the recording mechanism and sets the disc (12') in rotation by frictional contact with the rotating drum (8).

The disc (12') continues to rotate until 50 the pressure pulse or wave impinges the diaphragm of detector station D_3 and when this occurs relay R_3 is energized, armature switch (34) removed from contact (33) and the circuit (2₁) disrupted thereby deenergizing electro-magnet (16) and permitting restoration of disc (12), to braking position 55 with respect to brake-shoe (7).

From the preceding it is manifest, since 60 discs (12) and (12') are calibrated to give time readings, the rotation of the discs through a predetermined angle, during the passage of the wave from one station to the other will afford a correct reading of the difference in time of arrival of the pressure 65 pulse at the respective stations. The time

intervals being obtained, the results are plotted on the board with the proper scales.

In the meantime the operator has opened reversing switch S , released the locking devices in connection with relays R_1 , R_2 and R_3 and reset the discs (12) and (12'), making the proper zero corrections for the next shot as soon as these are known. 70

In the present embodiment two discs (12) and (12') are employed, it is to be understood however, one will suffice though the use of two is preferable, as a check on the first reading is thus made possible. 75

In conclusion it will be seen this invention provides a simple, efficient and accurate recording apparatus which will automatically function to provide the difference in time of arrival of a pressure pulse or wave at two or more detector stations and will eliminate the possibility of error and loss of time involved in the devices hereinbefore employed 80 for this purpose. 85

Although in the foregoing certain elements have been described as best adapted to perform the functions allotted to them, nevertheless it is to be understood that various minor changes may be resorted to within the scope of the appended claims without departing from or sacrificing any of the principles of 90 this invention. 95

Having described my invention what I claim as new and wish to secure by Letters Patent is:

1. A system of the character specified comprising a pair of detector stations located 100 at spaced and known points, a drum rotating at a constant speed, a movable indicating member located adjacent to and adapted to engage the drum and operable thereby a given distance in a predetermined time interval, impulse responsive means controlled 105 by the detector stations and including means for moving said indicating member, electrical connections between said detector stations and said impulse responsive means, 110 said connections including means to energize said impulse means when one of said stations is impinged by a pressure pulse or wave and to deenergize said impulse device upon impingement of the wave with the remaining station. 115

2. A system of the character specified comprising a pair of detector stations in the nature of compressional wave electro-responsive devices, located at spaced and known points, a drum, means to rotate said drum at a uniform rate of speed, a recording dial located adjacent to and adapted to engage the drum, an electro-magnetic member controlling the action of said dial, electrical 120 connections for said member, said connections including means controlled by one of said stations to energize said member and effect engagement between the dial and the drum whereby to rotate said drum when 125 130

one of the stations is impinged by a compressional wave and additional means to de-energize said member and stop the drum when the remaining station is impinged.

5 3. A system of the character specified comprising a pair of detector stations in the nature of compressional wave electro-responsive devices, said devices being located at spaced and known points, a drum, 10 means to rotate said drum at a uniform rate of speed, a recording dial located adjacent to and adapted to engage said drum, said dial being provided with time readings predicated on its angle of rotation, electro-magnetic 15 means for connecting said dial to and disconnecting it from said drum, electrical connections for said means, said connections including means controlled by said stations for energizing said electro-magnetic means 20 when one of said stations is impinged by a compressional wave and additional means effecting deenergization of said electro-magnetic means upon impingement of the wave with the remaining station, and a 25 switch mechanism cooperating with said stations to vary the order of their response.

4. A system of the character specified comprising a pair of detector stations in the nature of compressional wave electro-30 responsive devices, said devices being located at spaced and known points, a constantly moving surface actuated at a uniform rate of speed, a recording dial situated adjacent to and adapted to engage said surface, said dial being provided with time 35 readings predicated on its angle of rotation, electro-magnetic means for connecting said dial to and disconnecting it from said constantly moving surface electrical connections 40 for said means, said connections including means controlled by said stations for energizing said electro-magnetic means when one of said stations is impinged by a compressional wave and additional means effecting deenergization of said electro-magnetic 45 means upon impingement of the wave with the remaining station.

5. A system of the character specified comprising a pair of detector stations in the 50 nature of compressional wave electro-responsive devices, said devices being located at spaced and known points, a constantly moving surface actuated at a uniform rate of speed, a recording dial situated adjacent to and adapted to engage said surface, said 55 dial being provided with time readings pred-

icated on its angle of rotation, electro-magnetic means for connecting said dial to and disconnecting it from said drum, electrical connections for said means, said connections including means controlled by said stations for energizing said electro-magnetic means when one of the said stations is impinged by a compressional wave and additional means effecting deenergization of said electro-magnetic means upon impingement of the wave with the remaining station, and a switch mechanism cooperating with said stations to vary the order of their response.

6. A system of the character specified 70 comprising a pair of detector stations in the nature of compressional wave electro-responsive devices, said devices being located at spaced and known points, a timing device including a member moving at a uniform 75 rate of speed, an indicator adapted to give readings in time units directly, electro-magnetic means for connecting said indicator to and disconnecting it from said moving member, electrical connections between said compressional wave-responsive devices and said 80 electro-magnetic means, said connections including means for energizing said electro-magnetic means when one of said stations is impinged by a compressional wave and additional means effecting deenergization of 85 said electro-magnetic means upon impingement of the wave at the remaining station.

7. A system of the character specified 90 comprising a pair of detector stations in the nature of compressional wave electro-responsive devices, said devices being located at spaced and known points, a timing device including a member moving at a uniform 95 rate of speed, an indicator adapted to give 100 readings in time units directly, electro-magnetic means for connecting said indicator to and disconnecting it from said moving member, electrical connections between said compressional wave-responsive devices and said electro-magnetic means, said connections including means for energizing said electro-magnetic means when one of said stations is impinged by a compressional 105 wave and additional means effecting deenergization of said electro-magnetic means upon impingement of the wave at the remaining station, and a switch mechanism cooperating with said stations to vary the order of their response.

EDWARD B. STEPHENSON.
